UNITED STATES PATENT OFFICE.

CHARLES A. WULF, OF INDIANAPOLIS, INDIANA.

DISTRIBUTER FOR AUTOMOBILE ENGINE-STARTERS.

1,048,021.

Specification of Letters Patent. Patented Dec. 24, 1912.

Application filed December 16, 1911. Serial No. 666,224.

To all whom it may concern:

Be it known that I, CHARLES A. WULF, a citizen of the United States, residing at Indianapolis, in the county of Marion and 5 State of Indiana, have invented a new and useful Distributer for Automobile Engine-Starters, of which the following is a specification.

The object of my invention is to produce 10 in compact form an automatic distributor for insertion between a multiplicity of cylinders of an automobile engine and a manually manipulable pump by means of which a preliminary charge of explosive mixture 15 may be injected into that one (or more) of the cylinders in which the piston is in proper position to receive a fuel charge.

The accompanying drawings illustrate my 20 invention.

Figure 1 is a diagram or plan showing 25 the general arrangement of my apparatus in conjunction with a multiplicity of engine cylinders; Fig. 2 a section of the distributor on line 2—2 of Fig. 3; Fig. 3 a section on line 3—3 of Fig. 2; and Fig. 4 a fragmentary sectional detail showing the connection between one of the distributing pipes and one of the engine cylinders.

In the drawings, 10, 10 indicate the 30 several cylinders each of which, in the present instance, has its spark plug 11 mounted in a bushing 12 connected with the cylinder head and having a fuel pipe 13 leading into the bushing immediately adjacent the spark 35 plug. In each of these pipes 13 may be mounted a pet cock 14 each with an arm 15 so that the several arms may be connected together by a single push rod 16 extended back through the dash board 17 where it 40 may be readily manipulated.

My improved distributor comprises a main body 21 within which I form, for a four cylinder engine, two substantially parallel passages 22, 22, each of which is an inverted 45 U-shape or V-shape, the arms of each passage being comparatively short. In the outer end or lower end of each of these passages I mount a bushing or plug 23 provided with a valve seat 24 at its inner end adapted to receive a valve ball 25 which 50 loosely fits the passage 22 and is freely movable from end to end thereof so as to seat upon either one of the seats 24 at the opposite ends of the passage. Leading from 55 each passage 22 is a passage 26 and each of

these two passages 26 leads into a passage 27 through an intervening valve seat 28 upon which is mounted a check valve or ball 29 conveniently resting on its seat by gravity. The outer end of passage 27 is connected by a pipe 31 with a pump chamber 32 in which is mounted a piston 33. The chamber 32 communicates through a check valve 34 with a passage 35 which leads from a fuel supply tank 36.

I do not desire to be limited to any particular form of pumping mechanism by means of which fuel may be injected into the passage 27, but I believe the most convenient form will be that shown in Fig. 3, where the pump chamber 32 is paralleled by a pump chamber 37 within which is mounted a piston 38, the two pistons 33 and 38 being connected by a common handle 39. Leading from the pump chamber 37 is a small tube 41 which has its discharge end brought well down into the fuel chamber 36 so that the discharge end of the tube 41 will be submerged in the fuel, the arrangement of the pump being such that on the up-stroke piston 38 will inject air through passage 41 into the fuel, while piston 33 will suck the resulting mixture from the fuel chamber 36 into the pump chamber 32. On the down-stroke of the two pistons 37 and 38 fresh air will be drawn into chamber 37 and the mixture will be delivered from chamber 32 into pipe 31. Each of the plugs 23 will have one of the pipes 13 connected to it.

In order to relieve the pressures within the distributor when desired, I provide exhaust passages 42, 42 leading from the chambers 22 and provide a pet cock 43 arranged to open and close the passages 42 as clearly indicated in Figs. 2 and 3, this pet cock construction being conveniently made integral with the distributor.

In operation, with the pet cocks 14 open or, if no such pet cocks have been provided, balls 25 will be reciprocated in their passages 22 by the compressions within the respective cylinders so that, upon the compression in any one cylinder, free communication will be established between the interior of that cylinder and the corresponding passage 26 and at the same time communication will be cut off between that passage 26, and that cylinder within which the suction stroke is about to be performed. As a consequence, when the engine stops, if there is not suffi-

cient fuel within the engine to permit starting automatically by application of sparks within the cylinders in which the pistons are on their forward power strokes, the 5 operator, without taking any pains to determine which of the cylinders are in position to receive a fresh charge, may immediately manipulate the fuel pump shown in Fig. 3 to inject the charge of fuel into the engine. 10 This injection of fuel will automatically raise the two check valves 29 and fuel will pass into both of the passages 22 and will there be distributed, by reason of the positions of the two balls 25, into those two 15 cylinders in one of which compression last took place and in the other of which suction last took place. Thereupon the necessary sparks may be supplied to produce an explosion within the cylinder in which compression has been produced and the forward 20 movement of the engine will immediately produce compression in the other cylinder to which the charge of fuel has been delivered through my distributor so as to be 25 ready for firing as the piston in that cylinder passes the dead center.

In view of the fact that some objection might be raised to the possible noise of constant reciprocation of the valves 25, the pet 30 cocks 14 have been provided and these pet cocks would be normally held closed so that there would be no communication between the several cylinders and my distributor. When the engine is allowed to stop, however, 35 the operator would then open the several pet cocks, whereupon the pressures within the cylinders would serve to automatically shift the balls 25 to proper selective position.

It will be noticed that the apparatus 40 which I have produced is exceedingly simple to manufacture and that ordinary commercial balls may be used for the valves although it is to be understood that I have merely selected this type of valve as one of 45 a number of forms which might be used in

which the valve can be shifted from one seat to another to accomplish the purpose.

I claim as my invention:

1. An automobile starter distributor comprising a main body having a passage therein with two depending discharge ends, and also having a fuel supply passage communicating with the middle of said passage, a check valve arranged between said two passages, a pair of inwardly presented valve 55 seats arranged at the opposite ends of said first mentioned passage, and a valve mounted within said first mentioned passage and shiftable into position upon either of said seats to thereby establish connection between the supply passage and the other of said seats, whereby back pressure at either discharge end of said first mentioned passage will serve to propel the valve in said passage to the opposite seat. 65

2. An automobile starter distributor comprising a main body having a passage therein with two depending discharge ends, and also having a fuel supply passage communicating with the middle of said passage, a 70 pair of inwardly presented valve seats arranged at the opposite ends of said first mentioned passage, and a valve mounted within said first mentioned passage and shiftable into position upon either of said seats to 75 thereby establish connection between the supply passage and the other of said seats, whereby back pressure at either discharge end of said first mentioned passage will serve to propel the valve in said passage to 80 the opposite seat.

In witness whereof, I have hereunto set my hand and seal at Indianapolis, Indiana, this 14th day of December, A. D. one thousand nine hundred and eleven.

CHARLES A. WULF. [L. S.]
